UNITED STATES PATENT OFFICE.

KENNETH E. BEMIS AND ROY E. CHRISTOPHERSON, OF MINNEAPOLIS, MINNESOTA.

CHILD'S VEHICLE.

Application filed September 9, 1922. Serial No. 587,175.

To all whom it may concern:

Be it known that we, KENNETH E. BEMIS and ROY E. CHRISTOPHERSON, citizens of the United States, residing at Minneapolis, in 5 the county of Hennepin and State of Minnesota, have invented certain new and useful Improvements in Children's Vehicles; and we do hereby declare the following to be a full, clear, and exact description of the invention, such as will enable others skilled 10 in the art to which it appertains to make and use the same.

Our invention has for its object to provide a very simple and inexpensive toy motor cycle which, at the same time, is very durable and attractive, and may be ridden by a child and propelled by bringing his feet onto the floor or walk with a walking action.

20 To the above end, the invention consists of the novel devices and combinations of devices hereinafter described and defined in the claims:

In the accompanying drawings, which illustrate the invention, like characters indicate like parts throughout the several views.

Referring to the drawings:

Fig. 1 is a side elevation of the improved toy motor cycle with some parts broken away and sectioned;

Fig. 2 is a fragmentary plan view of the same;

Fig. 3 is a detail view in horizontal section taken on the line 3—3 of Fig. 1; and

35 Fig. 4 is a detail view in vertical section taken on the line 4—4 of Fig. 1.

The numerals 5 and 6, respectively, indicate longitudinally divided upper and lower frame bars, and the numeral 7 indicates a 40 sheet metal body member, the upper and lower edges of which are inserted between the members of said frame bars and rigidly secured thereto by rivets or otherwise.

A steering post 8, in the form of a yoke-like bar, is swivelled by a long headed pin 9 to a sleeve bearing 10 mounted in a rectangular skeleton head 11 which, as shown, is bent from a single bar fitted between the legs of the steering post 8 and rigidly secured thereto. The pin 9 extends through 50 bores in the transverse portions of the head 11 and is held in position by a cotter pin 12. The sleeve bearing 10 is supported on the lower transverse portion of the head 11 and is held against vertical movement on 55 the pin 9 by the upper portion of said head.

As shown, the sleeve bearing 10 is formed by folding a single sheet of metal, the longitudinal edge portions of which are extended radially outward to afford a pair of flanges 60 13, between which the front vertical edge portion of the body member 7 is inserted. The front end portions of the members of the top frame bar 5 and bottom frame bar 6 overlap the flanges 13, and rivets 14 are 65 extended through said frame bars, flanges and body member 7 to rigidly secure the sleeve bearing 10 thereto. The legs of the steering post 8, below the head 11, afford a front fork 15 for a front wheel 16 which is 70 journaled thereto.

The members of the top frame bar 5 and bottom frame bar 6, rearward of the body plate 7, are laterally spaced to afford upper and lower rear forks 17 and 18, respectively, 75 and to which forks is journaled a rear wheel 19. The wheels 16 and 19 are of the disc type and each is made up of two concavo-convex plates, the peripheries of which have formed thereon flanges 20, between which is 80 mounted a rubber tire 21.

A pair of handle bars 22, formed from a single metal bar, the ends of which are folded upon themselves to afford hand grips 23, is secured to the front face of the steering post 8 by a clamp in the form of a short bar 24, which bears against the back face of said steering post and is adjustably connected to the handle bars 22 of a pair of nut-equipped bolts 25.

90 A pressed sheet metal seat 26 is secured to the upper end of a longitudinally divided seat post 27, the members of which embrace the body plate 7 inward of the members of the frame bars 5 and 6 which are laterally bulged at 28 and 29, respectively, to receive the same. Nut-equipped bolts 30 are extended through aligned bores in the members of the upper and lower frame bars 5 and 6 and the body plate 7 and any one of 100 a plurality of holes 31 in the members of the seat post 27 for securing the same with the seat 26 in different vertical adjustments. Obviously, the seat post 27 affords a strut between the upper and lower frame bar 6 105 and also stiffens and holds the body plate 7.

On each side of the body plate 7 is illustrated, by means of paint, stenciling, lithographing, or otherwise, a dummy representation 32 showing all of the working parts 110 of the power unit of a motor cycle together with a gas tank 33 and a tool box 34.

What we claim is:

1. A child's vehicle having a body plate, the upper and lower edges of which are reinforced by upper and lower frame bars, respectively, and a seat post affording a strut for the upper and lower frame bars, said bars being extended rearward of the body plate and connected.
2. A child's vehicle having a body plate, the upper and lower edges of which are reinforced by upper and lower frame bars, respectively, and a seat post affording a strut for the upper and lower frame bars, said seat post being secured to the upper and lower frame bars for vertical adjustment.
3. A child's vehicle having a body plate, the upper and lower edges of which are reinforced by upper and lower frame bars, respectively, a front fork swivelled to the body plate, and upper and lower rear forks, said forks being integral extensions of the frame bars.
4. A child's vehicle having longitudinally divided upper and lower frame bars, and a body plate having its upper and lower edges inserted between the members of said bars and rigidly secured thereto, the members of said frame bars, rearward of the body plate,

being extended and laterally spaced to afford upper and lower rear forks.

5. The structure defined in claim 4 in further combination with a seat post arranged to afford a strut for the upper and lower frame bars.

6. The structure defined in claim 4 in further combination with a longitudinally divided seat post, the members of which embrace the body plate, the members of the frame bars being laterally bulged to receive and hold the members of the seat post.

7. The structure defined in claim 6 in which the seat post affords a strut for the upper and lower frame bars.

8. A toy motor cycle having longitudinally divided upper and lower frame bars, a body plate having its upper and lower edges inserted between the members of said bars and rigidly secured thereto, a sleeve bearing rigidly secured to the front end of the frame bars and the body plate, and a front fork swivelled in the sleeve bearing.

In testimony whereof we affix our signatures.

KENNETH E. BEMIS.
ROY E. CHRISTOPHERSON.
